UNITED STATES PATENT OFFICE.

JOHN T. POHLMAN, OF NEW HAVEN, CONNECTICUT.

METAL TUG FOR HARNESS.

SPECIFICATION forming part of Letters Patent No. 439,682, dated November 4, 1890.

Application filed July 24, 1890. Serial No. 359,759. (No model.)

To all whom it may concern:

Be it known that I, JOHN T. POHLMAN, a citizen of the United States, residing at New Haven, in the county of New Haven, in the 5 State of Connecticut, have invented a new and useful Metal Tug for Harnesses, of which the following is a specification.

The object of my invention is to provide a metal tug for harnesses of a simple and ornamental design, adapted to be readily attached to or disconnected from the harness-saddle and by pivotal connections therewith to permit the vibration of the shafts without oscillation of the saddle and consequent chafing of 15 the back of the horse.

The invention consists in the novel arrangement and combination of a metal supporting-strap, having the slotted pivot-socket, and the metal tug, having the T or toggle 20 pivot adapted thereto, as hereinafter more fully described and claimed.

In the accompanying drawings, forming a part of this specification, Figure 1 is a side view of my improved tug and supporting-strap 25 as connected in operation. Fig. 2 is a front elevation of Fig. 1, viewed from the side next to the horse when in use. Fig. 3 is an end view of the supporting-strap shown in Figs. 1 and 2. Figs. 4 and 5 are views of the supporting-strap and tug, illustrating the mode of attaching or connecting the said parts.

Referring to the drawings, A designates my improved tug, which is formed of malleable iron, brass, or other suitable metal, having the 35 ordinary circular or elliptical opening B to admit the shafts of the vehicle. On the lower side of the tug A is a suitable depending eye H, formed integral therewith, for the attachment of the ordinary shaft-girt C. On the upper side of the tug A, and formed integrally therewith, is a vertical neck or shank D, provided at the upper end with opposite lateral trunnions e e, extending parallel with the shaft-opening B and forming with the said 40 neck D a T-shaped toggle-head n. The supporting-strap F is formed of malleable iron, brass, or other suitable metal, and is of the same width as the tug A. In the lower part thereof is an opening or chamber g, extending 45 through it in the direction of its width, as shown. The width of said opening g corresponds to the diameter of the trunnions, and 50 the height of the said opening or chamber or its dimensions lengthwise of the supporting-strap corresponds to the length of the toggle-head n. Centrally on one side of the supporting-strap F is a vertical slot K, communicating with said chamber g, extending from the lower end of the strap to the upper side of the opening g and corresponding in width 55 to the diameter of the trunnion. Said slot is adapted to admit the toggle-head or trunnions into the opening g, as shown in Fig. 4, and the said opening g is adapted to permit the said toggle-head to turn therein through a quarter-revolution as the tug A is turned from the position shown in Fig. 4 to that shown in Fig. 5, which will bring said toggle-head at right angles to the slot K, as shown in said Fig. 5, and the toggle-head and trunnions will thus 60 be toggled in the supporting-strap F. The lower side of said opening is made circular to receive and form bearings for the said trunnions e e, which, after the tug is turned to the position shown in Fig. 5, may be dropped down 65 into said bearings, and the tug may then be swung on said trunnions down to the position shown in Fig. 1, the slot K permitting the neck or shank D to swing, as described. The opposite side of the strap is slotted up a little 70 way from the bottom to form a clearance-space m for the said shank to swing in when the tug is oscillated past a vertical plane 75 lengthwise through the strap F. The upper part of the strap F has two rectangular apertures r r formed therein, separated by a cross-bridge u, having a spur t at the back thereof, thus providing for the attachment of the saddle-strap, which may be passed through the apertures with the spur penetrating it, 80 thus holding it in place. Said supporting-strap F is fastened to the saddle-girt with the slot K toward the horse, and in operation the 85 tug cannot be detached therefrom, except by being swung into a horizontal position toward 90 the horse and then revolved a quarter-turn to a position shown in Fig. 4. The strap and the trunnions of the toggle-head form a hinged joint, which permits the shafts to swing without oscillating the saddle upon the back of 95 the horse. By the peculiar construction of the toggle-head and trunnions and the strap having its pivot-chamber g adapted thereto the parts when attached are hinged together 100

without involving the use of a rivet or pivotal piece.

The parts are simple in construction and can be readily polished, plated, and connected together, and may be cheaply and conveniently applied to harnesses old or new, and is of neat and ornamental design.

Having fully described my invention, what I desire to claim and secure by Letters Patent, is—

1. The combination of the metal tug provided on its upper side with a vertical neck or shank having lateral trunnions in the plane of the shaft-opening forming a T-shaped toggle-head, and the metal supporting-strap adapted for attachment to the harness-saddle formed with an opening or chamber in its lower part, having a central vertical slot opening thereinto at the side and bottom thereof, adapted to admit the toggle-head of the tug into said chamber, the chamber corresponding to the said head and permitting the quarter-turn thereof, having bearings at its lower side to support the toggle-trunnions, whereby they

are retained in engagement with and hinged to the supporting-strap, as specified.

2. The combination of the metal tug provided on its upper side with a vertical neck or shank having lateral trunnions in the plane of the shaft-opening forming a T-shaped toggle-head, and the metal supporting-strap having eyes or apertures in its upper part for attachment to the harness-saddle formed with an opening or chamber *g* in its lower part, having the central vertical slot *K* opening 35 thereinto at the side and bottom thereof, adapted to admit the toggle-head of the tug into said chamber, the chamber corresponding to the said head and permitting the quarter-turn thereof, and having bearings at its 40 lower side to support the toggled trunnions, whereby they are retained in engagement with and hinged to the strap, as specified.

JOHN T. POHLMAN.
